UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

ORE-CRUSHER.

1,034,552.

Specification of Letters Patent. Patented Aug. 6, 1912.

Application filed August 28, 1911. Serial No. 646,530.

To all whom it may concern:

Be it known that I, MILTON F. WILLIAMS, a citizen of the United States, residing at St. Louis, Missouri, have invented a certain 5 new and useful Improvement in Ore-Crushers, of which the following is a full, clear, and exact description, such as will enable others skilled in the art to which it appertains to make and use the same, reference being had to the accompanying drawings, forming part of this specification, in which—

Figure 1 is a side elevational view of my improved ore crusher partly in section. 15 Fig. 2 is an end elevational view looking at the discharge end of the machine. Fig. 3 is a vertical cross sectional view.

This invention relates to a new and useful improvement in ore crushers designed particularly for crushing or disintegrating conglomerate ores, the object being to construct a machine of the character described so that it will be simple, cheap and easy of repair and one which will confine the 25 dust incident to the reduction of the ores.

With these objects in view the invention consists in the construction, arrangement and combination of the several parts all as will hereinafter be described and afterward pointed out in the claims.

In the drawings, 1 indicates the sleepers upon which the frame work is mounted this frame work preferably consisting of commercially rolled flanged members appropriately riveted together to provide supports for the bearings in which the removable parts of the machine are mounted.

2 indicates the side frame members and 3 the end frame members.

40 4 are universal bearings mounted upon the end frame members in which is journaled a shaft 5 carrying a pulley 6 at one end. On this shaft 5, within the reducing chamber are strung a series of flexible hammers 45 7 preferably arranged in spiral series, said hammers comprising head portions which are connected by chains 8 to the opposite side of split collars clamped on the shaft.

The grinding cylinder is composed of a 50 series of longitudinally disposed bars 10 appropriately spaced apart and whose ends are mounted in clamping rings 11 which rings are provided with track portions 12 for operating with supporting wheels 13. These 55 wheels 13 are mounted on shafts 14 arranged

in suitable bearings supported by the end framing so that there are two wheels at each end of the cylinder. Each of the shafts 14 carries a sprocket wheel 15 over which passes a chain 16 for revolving the shafts 14 60 in unison. A pulley 17 is mounted on one of the shafts 14 by which the power is communicated thereto for rotating the grinding cylinder.

18 indicates a housing preferably of sheet 65 metal and flanged longitudinally as shown in Fig. 3 whereby said housing is connected and supported by the side framing of the machine. The lower portion of the housing is in the form of a discharge trough 70 through which the material passing between the bars 10 drops onto a conveyer belt or into a receptacle located under the machine.

The material to be disintegrated is fed into one end of the machine through a hopper 19 and is subjected to the action of the hammers or beaters, the cylinder being rotated in the meantime so as to tumble the material in the reducing chamber and present different faces thereof to the action of 80 the hammers. As the material is fed into the machine, it practically builds up a bed in the bottom of the cylinder and as this bed increases in height it will overflow at the discharge end of the machine so that any 85 uncrushable material in the machine will pass out as tailings. The discharge end of the machine is therefore provided with a restricted opening formed by a flanged ring 90 20 having inwardly and outwardly flared rims so as to provide an external V shaped groove.

21 indicates a stationary end wall having converging flanges extending in the V shaped groove said wall also being provided 95 with an opening for the passage of shaft 5. This wall forms a support for the discharge spout 22 through which the tailings pass.

In operation the shaft and cylinder are preferably driven at different speeds, as 100 determined by the character of ore being operated upon. In practice I have found that 500 revolutions per minute for the shaft 5 and about 200 revolutions per minute for the grinding cylinder will prove very effective.

What I claim is:

1. In a device of the class described, a casing provided at one end with a feed opening, at its bottom a discharge opening, and 110

at the other end a second discharge opening, a grinding cylinder mounted therein and communicating at one end with the feed opening and by openings through its sides 5 with the bottom discharge opening, said cylinder being provided with an annular collar at the discharge end which collar is provided with a restricted annular opening, and having an outwardly extending flange 10 projecting into the discharge opening.

2. In a device of the class described, a rotary grinding cylinder, a revoluble shaft provided with hammers mounted therein, a

casing surrounding said cylinder, a stationary end wall having an annular converging flange, and a flanged ring mounted upon said cylinder and having an outwardly flared rim extending within said annular flange. 15

In testimony whereof I hereunto affix my signature in the presence of two witnesses, this 24th day of August, 1911.

MILTON F. WILLIAMS.
